DESIGN FOR A GLOVE

Elias Breath, New York, N. Y.

Application October 1, 1935, Serial No. 58,773

Term of patent 3½ years

To all whom it may concern:

Be it known that I, Elias Breath, a citizen of the United States of America, residing in Manhattan, county of New York, and State of New York, have invented a new, original, and ornamental Design for a Glove, of which the following is a specification, reference being had to the accompanying drawing, forming part thereof, wherein,

The dominant feature of my design resides in the finger-nail appearance of the contrasting inserts on the back tips of the finger portions of the glove.

I claim:

The ornamental design for a glove, substantially as shown and described.

ELIAS BREATH.
